UNITED STATES PATENT OFFICE.

FRANK W. WHITCHER, OF BOSTON, MASSACHUSETTS, ASSIGNOR TO FRANK W. WHITCHER COMPANY, OF BOSTON, MASSACHUSETTS, A CORPORATION OF MAINE.

LACING.

No. 902,190.

Specification of Letters Patent.

Patented Oct. 27, 1908.

Application filed May 16, 1906. Serial No. 317,094.

To all whom it may concern:

Be it known that I, FRANK W. WHITCHER, a citizen of the United States, residing at Boston, county of Suffolk, State of Massachusetts, have invented a certain new and useful Improvement in Lacings, of which the following is a specification, reference being had therein to the accompanying drawings.

My invention has for its object the production of a new and improved lacing for use with boots and shoes, corsets, and the like, of the type frequently known as a "composition tip."

Composition tips are formed by applying to the end of a suitable length of material a proper amount of some suitable composition, and then subjecting the end of the lacing to pressure in dies of proper shape, which gives to the tip the desired shape and renders it sufficiently stiff and unyielding, so that it may be readily passed through the eyelets in the article with which it is to be used. The application of composition to the end of the lacing also prevents the fabric of which the lacing is composed from spreading out or fraying, and maintains it in condition to be readily inserted in the holes in the article with which it is to be used.

I also contemplate the manufacture of my improved lacing tips from certain fabrics composed of fibers which when properly compressed become sufficiently solidified without the use of composition.

The invention will be fully understood from the following specification taken in connection with the accompanying drawings, and the novel features thereof are pointed out and clearly defined in the claim at the close of the specification.

40 In the drawings,—Figure 1 is a side view of the tip of a completed lacing embodying my invention. Fig. 2 is a longitudinal section of the material of which the lacing tip is composed, the end portion of the said material being folded back into the position which it assumes before it is filled with the composition and subjected to pressure in the dies. Fig. 3 is a longitudinal section of the completed lacing tip embodying my invention.

50 Referring to the drawings,—the body of the lacing is indicated by the reference character A. The lacing may be made of any suitable material, preferably the ordinary tubular braided fabric. After the lacing A has been cut to the desired length, the end

portion B of the lacing is turned back upon itself that is, turned inside out for such a distance as is required to form a lacing tip of the length desired. A suitable amount of composition of the proper kind is then applied to the turned back end of the lacing. This composition may be made of any suitable material, but is preferably one which will permeate the fabric composing the lacing, and will harden and stiffen when subjected to pressure. The composition may be applied to the exterior of the lacing, but I find that best results are obtained by inserting a suitable amount of the composition within the hollow end of the lacing. The end of the lacing is then subjected to pressure in dies of suitable form. This pressure applied by the die to the fabric composing the lacing and to the composition applied thereto forces the composition through the material and gives to the tip the proper form, as seen at C in Fig. 1, and solidifies the lacing material and the composition, so that a stiff and unyielding tip of a horn-like consistency is formed which resists bending, prevents the fabric from raveling, and is impermeable by moisture.

While I have described my improved lacing tip as a composition tip, that is one composed of fabric permeated or treated with some suitable composition and compressed, I do not wish to be limited to the use of composition, because I believe that a satisfactory tip may be made of fabric composed of certain kinds of fiber which when subjected to proper pressure for the right length of time will be solidified as desired without the application of separate composition.

I believe that lacing tips formed in the manner which I have described are much cheaper to manufacture than those heretofore made, because the fabric may be turned backward at the end of the tubular lacing much more readily than it can be folded into any other form so far as now known to me.

What I claim is:

The improved tip for lacings consisting of a portion of tubular fabric folded back on itself on the outside and compressed.

In testimony whereof I affix my signature, in presence of two witnesses.

FRANK W. WHITCHER.
